UNITED STATES PATENT OFFICE.

FRANK A. MONAHAN, OF ST. LOUIS, MISSOURI, ASSIGNOR TO THE J. H. POCOCK CAN COMPANY, OF SAME PLACE.

DESIGN FOR A CAN.

SPECIFICATION forming part of Design No. 19,738, dated April 1, 1890.

Application filed March 1, 1890. Serial No. 342,303. Term of patent 3½ years.

To all whom it may concern:

Be it known that I, FRANK A. MONAHAN, a citizen of the United States, residing at St. Louis, in the State of Missouri, have invented and produced a new and original Design for Oil-Cans, of which the following is a full, clear, and exact description, reference being had to the accompanying drawing, forming a part thereof.

10 The figure is a perspective view of an oil-can showing my design.

The leading feature of my design is a cylindrical figure surmounted by a cone and having an annular depression and a raised annular projection located at the upper terminal of said cylindrical figure.

15 1 is the cylindrical figure, surmounted by the cone 2, and having the raised band or annular projection 3 at its upper terminal and forming the annular depression 9 at the base of said cone. The lower terminal of the cylindrical figure is surrounded by an annular flat-surfaced band 4, and the apex of the cone 2 is surmounted by a smaller cylindrical projection 6, presenting a ribbed or corrugated

appearance. A curved projection 7, having also a ribbed or corrugated extremity, radiates from said cone at about the center of its height, and a V-shaped figure 10 is located between said curved projection and the outer 30 surface of said cone.

8 is an L-shaped projection radiating from said cone in a direction opposite to that in which the curved projection 7 radiates.

5 and 12 are angular figures resembling 35 beads, which encircle the cone 2.

What I claim is—

The design for a can, consisting of the cylindrical figure surmounted by a cone-shaped figure, said cone-shaped figure being provided 40 with beads 5 and 12, an annular depression 9, and an annular projection 3 at the base of the cone, substantially as shown and described.

In testimony whereof I affix my signature in presence of two witnesses.

FRANK A. MONAHAN.
